SWITCH ENCLOSURE

David E. Scott, Royal Oak, Mich., assignor to Square D
Company, Park Ridge, Ill., a corporation of Michigan

Filed May 17, 1962, Ser. No. 70,180

Term of patent 14 years

(Cl. D26—13)

FIG. 1

FIG. 2

FIG. 3

FIG. 4

FIG. 1 is a front perspective view of a switch enclosure showing my new design.

FIG. 2 is a front elevational view thereof.

FIG. 3 is a side elevational view thereof.

FIG. 4 is a rear elevational view thereof.

The essential features of the design are shown in full lines.

I claim:

The ornamental design for a switch enclosure, substantially as shown and described.
